UNITED STATES PATENT OFFICE.

ANDREW SCHUEHLE, OF MINNEAPOLIS, MINNESOTA.

CONTROLLING DEVICE FOR CASEMENT WINDOWS.

Application filed February 23, 1923. Serial No. 620,722.

To all whom it may concern:

Be it known that I, ANDREW SCHUEHLE, a citizen of the United States, residing at Minneapolis, in the county of Hennepin 5 and State of Minnesota, have invented certain new and useful Improvements in Controlling Devices for Casement Windows; and I do hereby declare the following to be a full, clear, and exact description of the 10 invention, such as will enable others skilled in the art to which it appertains to make and use the same.

This invention relates to a window opening and closing device and while the invention 15 is applicable to any swinging door, window, screen or similar hinged member, it is more particularly adapted for casement windows. Such windows are usually mounted in casements so as to swing outwardly from the outer side thereof and such casements are frequently provided with a screen or storm window at the inner side thereof. Owing to the presence of the screen 20 or storm window, it is quite inconvenient to reach the casement window to manually operate the same. For this reason it is most desirable to have some operating means for opening, closing and locking a window which can be manipulated without disturbing 25 the inner screen or window. It is also quite common to equip such casement windows with spring hinges whereby they will automatically swing outwardly when partially opened.

30 It is an object of this invention, therefore, to provide a device by which the casement window may be pushed to partly open position so that the same can be swung open by its spring hinges and to provide a closing 35 means for the window, both of which means can be operated without disturbing the inner window.

40 It is also an object of the invention to provide means for opening and closing a casement window which is disposed in and operated through the casement of said window.

45 It is still another object of the invention to provide such a device operating through the casement of the window comprising a 50 locking means to hold the window in closed position.

55 It is more specifically an object of the invention to provide an opening means for such a casement window comprising a plunger member extending through and slidably

through the casement and adapted to engage the window together with a flexible cord associated with said plunger for closing the window, which plunger is adapted to lock the window in position and which cord may 60 also be provided with a take-up device.

These and other objects and advantages of the invention will be fully set forth in the following description made in connection with the accompanying drawings, in 65 which like reference characters refer to the same parts throughout the different views, and in which,

Fig. 1 is a view in horizontal section through a window casement and window 70 showing the latter in open position, the closed position of the window being indicated in dotted lines;

Fig. 2 is a view in front elevation of one form of the device, as seen from the inside 75 of the window casement;

Fig. 3 is a view in front elevation of a modified form of the device;

Fig. 4 is a central vertical section of Fig. 3, a small portion thereof being shown in 80 side elevation;

Fig. 5 is a fragmentary horizontal section similar to that shown in Fig. 1, and shown on an enlarged scale;

Fig. 6 is a vertical section taken on the 85 line 6—6 of Fig. 5, as indicated by the arrows;

Fig. 7 is a vertical section taken on the line 7—7 of Fig. 5, as indicated by the 90 arrows;

Fig. 8 is a view in elevation taken substantially on the line 8—8 of Fig. 5, as indicated by the arrows; and

Fig. 9 is a partial view in front elevation of the device shown in Fig. 3 as seen from 95 the inside of the window casement shown on an enlarged scale.

Referring to the drawings, in Fig. 1 is shown a portion of a wall 1 in which the window casement having the vertical portions 2 and 3 is mounted. A window sash 4 carrying a glass 5 is hinged to the window casement by hinges 6 preferably of the spring hinge type, which sash 4 fits in the usual recesses formed in the members 2 and 3, as indicated by dotted lines in Fig. 1. An inner sash 7 is fitted in recesses in the inner sides of the casement portions 2 and 3, which sash may carry a glass as shown, or a screen.

105

110

In accordance with the present invention, spaced sleeves 8 and 9 are mounted in the member 2 at the inner and outer sides thereof and a hollow plunger member 10 is adapted to slide through said sleeves and be guided thereby, which plunger member thus extends through and is slidable in the casement. Said plunger member 10 has a handle 11 secured thereto at its inner end and is also provided adjacent said handle with oppositely disposed projecting ribs 12. In the embodiment of the invention illustrated, the plunger 10 is of cylindrical shape and fits in cylindrical passages in the sleeves 8 and 9 and the sleeve 8 is further provided with oppositely disposed passages 13 in which the ribs or projections 12 are adapted to slide. The sleeve 8 is provided at its outer end with a small projecting pin or stop 14 adjacent the upper passage 13, which pin is adapted to be contacted by one of the ribs 12 when said ribs are in position to align with the passages 13. At its outer end, the plunger 10 has secured thereto spaced collars 15 and 16 between which is also rigidly secured to the plunger a latch or locking member 17 of bluntly pointed shape and which projects at one side of said plunger.

The edge of the sash 4 opposite the hinged side thereof is provided with a recess receiving a recessed plate 18. In the bottom of the recess in said plate a slot 19 is formed, the outer side 20 of which extends at an angle to the vertical side of the sash 4 and this side is adapted to be contacted by the side of the latch 17 when the window is in closed position. The plate 18 and the recess therein also has a side plate 21 forming a pocket 22 in said plate and a knot or other stop member 23 on the end of a flexible cord 24 is adapted to be disposed in said recess. The plate 21 is provided with a vertical slot through which the cord 24 passes and a knot or stop member 23 is adapted to be placed in said recess and plate by being inserted through a T-shaped slot 25 formed in the front portion 26 of the plate 18. The plate 18 is secured in the sash 4 by suitable screws, the heads of which are countersunk in said plate. The cord 24 passes through the plunger 10 and said plunger is provided at its inner end with an opening 27 through the bottom thereof through which said cord passes. A take-up device preferably is provided for the cord 24 and said cord is adapted to pass over a groove guiding and holding bracket or knob 28 secured to the front of the casing. While any convenient form of take-up device could be used, in the embodiment of the invention illustrated, the cord 24 passes through an opening 29 and around a narrow reel 30 mounted in a suitable casing 31 secured in the casement, which reel is preferably placed under tension to

wind up the cord by a torsion spring 32 secured to the drum and to a shaft 33 mounted in the casing 31 on which the reel turns.

In operation, assuming that the sash 4 of the window is in closed position and locked, as shown in Fig. 5, the handle 11 will be in down-turned position, as shown in Fig. 9. If now it be desired to open the window, the handle 11 will be turned in a counter-clockwise direction through substantially ninety degrees and the projection 12 will contact the stop 14. The plunger 10 can now be pushed outwardly sliding in sleeves 8 and 9 and the projections 12 sliding in openings 13. The end collar 16 on the plunger and the end of the plunger will now contact with the plate 21 secured in the sash 4 and said sash will be pushed outwardly from the casement. After said sash has been partially opened it will be free to swing out and will be swung outwardly by the hinged spring 6. The cord 24 will be carried outwardly as the window swings open. If it be desired to close the window, the cord 24 will be grasped above the guide member 28 and then pulled inwardly. This will swing the window to substantially closed position and handle 11 can then be swung downwardly in a clockwise direction. The latch member 17 will then contact the side 20 of opening 19 and owing to the inclined angle of its side, the latch 17 will act to cam the window tightly to closed position and lock the same in such position. The spring drum 30 will wind up the cord so that the device will then occupy substantially the position shown in Figs. 4, 5 and 9.

In the modification shown in Figs. 2 and 9, the take-up device for the cord is not used but the end of the cord passes through the handle 34 and is provided with an ornamental tassel 35. The cord is shown in said figure with the window in open position and the handle 34 turned downwardly.

From the above description it is seen that applicant has provided a simple and efficient means for opening, closing and locking a window. The opening movement of the device is quite positive and the sash 4 can be pushed open no matter how tightly it is held in position. If desired, the cord can be wrapped around the member 28 which will then form a cord holder and the window can thus be held in various positions. With the device, the outer window can be easily manipulated as required without disturbing the inner screen or storm window. The parts of the device are few, simple and easily made and the device is constructed to form an ornamental appearance at the inner side of the casement.

It will be understood that various changes may be made in the form, details, arrangement and proportions of the parts without departing from the scope of applicant's in-

vention, which, generally stated, consists in the matter shown and described and set forth in the appended claims.

What is claimed is:

5. 1. The combination with a hinged window and the casement thereof, said casement having an opening therethrough of substantially uniform cross section, of a rectilinear plunger extending through and 10 slidable in said opening in said casement and adapted to abut said window adjacent its free edge whereby said window can be pressed outwardly to partially open position by said plunger.
15. 2. The structure set forth in claim 1, a keeper on said window, and said plunger having a locking device thereon adapted to be brought by a turning movement of said plunger about its longitudinal axis into 20 locking engagement with said keeper when the window is in closed position and to lock the window in such position.
25. 3. The combination with a window hinged along one vertical side thereof and a casement for said window, of a rectilinear plunger fitting in and slidable through an opening extending in a laterally inclined direction through the side of said casement with which the free edge of the window engages, 30 said plunger being adapted to abut against the inner side of the window adjacent its free edge and push the same to partially open position.
35. 4. The structure set forth in claim 1, and a flexible cord passing through said plunger and attached to the window and adapted to be pulled to close the window, and adapted to hold the same in various positions.
40. 5. The combination with a hinged window and the casement thereof, of a plunger extending through and slidable in said casement and adapted to abut said window adjacent its free edge, a flexible cord passing through said plunger and attached to the 45 window and adapted to be pulled to close the window and adapted to hold the same in various positions, and means for taking up the cord at the inner end of said plunger.
50. 6. The structure set forth in claim 5, said means comprising a spring actuated drum on which said cord is wound.
55. 7. The combination with a hinged window spring actuated to open position and the casement thereof, of a hollow plunger extending through and slidable in said casement adapted to contact the window sash and press the same outwardly to partially open position, a sleeve in said casement in which said plunger slides, a keeper on said window, a locking latch on said plunger adapted by rotation of said plunger about its longitudinal axis to engage said keeper when the window is in closed position, a
- projection on said plunger, and a passage in said sleeve with which said projection is adapted to align and in which it is adapted to slide when the latch is in unlocking position.
8. The structure set forth in claim 7, and a stop on said sleeve engageable by said projection on the plunger when said projection and passage are in alignment.
9. The structure set forth in claim 7, a handle on the inner end of said plunger and a cord passing through said plunger and attached to the window and adapted to be pulled for closing said window, and adapted to hold the same in various positions.
10. The combination with a hinged window that is spring pressed to open position, and the casement thereof, of a member extending through and slidable in said casement, and adapted to contact the window adjacent the side opposite to that on which it is hinged, whereby said window can be pressed outwardly by said member, sleeves in said casement forming guiding means for said member, and flexible means passing through said casement parallel with said plunger adapted to close the window.
11. The combination with an outwardly swinging window and the casement thereof, of a rectilinear member normally disposed in and extending through and slidable in said casement adapted to abut and be pushed against the window adjacent its free edge to open the same and a locking means for the window when in closed position carried by said plunger and movable therewith.
12. The structure set forth in claim 11, and means extending through said member attached to the window for closing the same.
13. The combination with a hinged window and the casement thereof, of rigid means extending through and movable in said casement and adapted to contact said window to press the same to partially open position, and flexible means extending through said rigid means adapted to close said window and hold the same in partially open position.
14. The combination with a hinged window and the casement thereof, of a rigid rectilinear plunger disposed in said casement and movable transversely thereof and adapted to press against the window adjacent its free edge and move the same to partially open position, a handle at the inside of said casement for moving said member, a flexible member fastened to said window for closing the same and holding the same in various open positions, said flexible member being disposed in said plunger and a take-up device for said flexible member.

In testimony whereof I affix my signature.
ANDREW SCHUEHLE.
